AUTOMATIC TELEPHONE SYSTEM

Eugen Jauch, Berlin-Siemensstadt, Germany, assignor to Fides Gesellschaft für die Verwaltung und Verwertung von gewerblichen Schutzrechten m. b. H., Berlin, Germany

Application November 15, 1938, Serial No. 240,572
In Germany November 1, 1937

10 Claims. (Cl. 179—18)

The invention relates to a circuit arrangement for automatic telephone systems in which connections of different value can be set up, e. g., local and trunk connections.

5 The invention concerns the control of the extension of calling current to the calling set according to the value of the incoming connection; and this is done by associating switching means with the calling line, which are influenced over 10 the selector which is seized, according to the value of the incoming connection and determine which kind of calling current is to be extended to the desired subscriber's set.

The arrangement is such that the switching 15 means, when they come into effect, inter-change the conductors of the junction lines of the calling subscribers. Preferably the switching means is influenced over the test lead of the final selector which is seized, to which earth potential 20 is connected over the test relay of the selector when a low valued connection is concerned, while with a high valued connection earth potential is connected directly. The characterizing of the 25 value of the connection also depends on whether the low resistance winding of the test relay in the test conductor is connected to the final selector or not. Since it is difficult to control the switch means in series with the test conductor directly in dependence on whether the test 30 relay is connected or not as in the two cases the current ratios are only slightly different, the system is arranged so that switching means in the form of a switching relay first comes into effect with each type of incoming connection but 35 then, however, in connections of one kind, e. g., high valued connections, is immediately disconnected. In order to carry out these switching operations, according to the invention the switching relay has an associated auxiliary relay which, 40 in the case of one particular connection, makes the switching relay ineffective by short circuiting the energizing winding of this relay and connecting the holding winding of the switching relay parallel to the switch means in the test conductor of the seized final selector. Since in the 45 case of high valued connections these lead directly to earth potential, the holding winding of the switching relay is short-circuited in such cases so that the switching relay is released.

50 The arrangement according to the invention can be used with advantage particularly in systems in which the call current is connected to one conductor of the junction line on a high valued connection and to the other conductor on a low valued connection. In such systems there

exists the special difficulty of using two junctions by which the subscriber is called over one conductor and earth. In order to insure the calling of the desired subscriber of a two-junction arrangement, in such cases, according to the invention, calling current is connected to the selector in a different manner for different valued connections and is disconnected by changing over the leads of the common junction line leading to both subscribers in common in dependence on the value of the incoming connection.

The invention can also be used with advantage in systems in which the calling current is connected in the same way to the junction lines on both high and low valued connections. In this case a differentiation in the characterizing of the incoming connections of different value is made possible by connecting different calling members, characterizing the type of incoming connection, in dependence on the extension of 20 the calling current to the calling subscriber by means of the switching relay according to the value of the incoming connection.

The combination local and trunk final selectors OFLW1 of Fig. 1 and OFLW2 of Fig. 2 may be 25 of the well known Strowger type final selector such as is disclosed in the Taylor Patent 2,113,119, issued April 5, 1938, modified slightly to meet the requirements of this invention. Referring to Figs. 1 and 2 of the Taylor patent, it is to be 30 noted that the final selector may be seized over two paths, one including the negative 1, positive 1, and P1 conductors and the other path including the negative 2, positive 2, and P2 conductors. In accordance with the present invention, it will be assumed that when local or low valued connections are extended to the final selector they will always seize the final selector over conductors positive 1, negative 1, and P1 and when trunk or high valued connections are 40 extended they will always seize the final selector over conductors positive 2, negative 2 and P2.

The relay WS of the Taylor patent is provided in series with the positive 2 conductor and is energized whenever the switch is seized over the 45 path including this conductor to determine the wiper set to be used in extending the connection to the desired subscriber. In the present invention, however, the relay WS may be utilized to discriminate between low and high valued connections instead of the wiper set to be used.

When used in the final selector OFLW1 of Fig. 1, the relay WS may be modified to include contacts 1n, 2n and 3n which would be normally closed and contacts 14h, 15h and 16h which 55

- would be normally open contacts. Therefore, when a local or low valued connection is extended to the final selector OFLW1, the contacts 1n, 2n, and 3n would be closed and when 5 a trunk or high valued connection is extended to the final selector, relay WS would energize to disconnect contacts 1n, 2n and 3n and to connect contacts 14h, 15h and 16h for the purpose to be described hereinafter.
- 10 When used in the final selector OFLW2 of Fig. 2 the relay WS may be modified to include contacts 18n, n, and 21n which would be normally closed and contacts 17h, h and 25h which would be normally open contacts. When a low valued 15 connection is extended to the final selector OFLW2, the contacts 18n, n, and 21n would be closed and when a trunk or high valued connection is extended to the final selector relay WS would energize to disconnect contacts 13n, n, and 20 21n and to connect contacts 17h, h, and 25h for the purpose to be described hereinafter.

It should be understood that the above method of discrimination is only one of a number of arrangements well known in the art for performing 25 a specific controlling function in a selector, which is determined over one of a plurality of paths over which the selector may be seized.

Embodiments of the invention are shown in the 30 accompanying drawing. In the drawing all details not necessary for the understanding of the invention are not shown.

In Fig. 1 an arrangement for two different kinds of junctions is shown, which are connected to a combination local and trunk final selector 35 (OFLW) in which the calling current is connected to the b-conductor for high valued connections and to the a-conductor for low valued connections.

Fig. 2 shows an arrangement for an individual 40 subscriber's connection in which several calling members are provided which are connected according to the value of the incoming connection.

The method of working of the arrangements shown in the embodiments is as follows:

45 In Fig. 1 after the setting of the final selector (OFLW) by an incoming low valued connection and after testing to see whether the line is free in dependence on the control switch of this selector the contacts 1n, 2n and 3n are closed to 50 send out calling current. If, for example, the subscriber Tn1 is called the following circuit is made: earth, battery, relay T1 of the preselector, c-conductor, relay F1 (winding I), contacts 4g1, 5f1, c-arm of the line selector on contact 1, contact 55 3n, relay P1, earth. In this circuit the switching relay F1 operates and opens its contact 5f1. In this way the relay G1 is energized in series with relay F1 by way of its winding I and by closing its contact 6g1, short-circuits the winding I of the relay F1. The relay G1 further closes the contact 7g1 and thus connects its winding II and also the winding II of the switching relay F1; these two windings which are connected with one another in series are now in parallel to the 60 switching devices arranged in the test circuit in the final selector.

Since in the above case a low valued connection is concerned the relay P1 is connected in the test path of the final selector over the contact 3n. 70 Parallel to this relay, relay F1 is maintained energized over its winding II so that contacts 8f1 and 9f1 shifted to their operated positions, remain in these positions and switch through the lines to the desired subscriber's junction. The 75 alternating calling current now connected from

the final selector over the contact 1n to the a-lead extends therefore from the calling current source over: contact 1n, a-arm of the final selector to contact 1, contact 8f1, a-lead of the junction line, contact 10u2, relay U1, subscriber Tn1 over the condenser K1, in parallel to the balancing coil Dr1, contact 11u1 to earth. The subscriber Tn1 is therefore called. When he replies, relay U1 is operated and over the contact 11u1 in its operated position connects the subscriber Tn1 to the junction line, while by opening the contact 12u1 disconnects the second subscriber from the common junction line.

When the connection is terminated the winding I of the relay G1 is still connected in series 15 with this winding II and the winding II of the relay F1 after the release of the final selector. Since the relay G1 is a differential relay the two windings are in opposition so that the relay G1 restores. Thus the contact 7g1 is also opened and 20 the holding circuit for the relays F1 and G1 is interrupted. The switching device is therefore in its normal position.

If the subscriber Tn2 is called for a low valued 25 connection corresponding switching operations are performed which are differentiated from the operations described for subscriber Tn1 in so far as the final selector is not set on contact 1 but on contact 2. The calling current to the subscriber Tn2 then extends from the calling current source over: contact 2n, a-arm of the final selector to contact 2, contact 9f1 in its operated position, b-conductor of the junction line, contact 12u1, relay U2, subscriber's set Tn2, condenser K2, contact 13u2 to earth. When the 30 calling subscriber lifts up his receiver relay U2 energizes and connects the subscriber to the common junction line over contact 13u2 and over contact 10u2 disconnects the second subscriber Tn1.

In the case of an incoming high valued connection (trunk connection) to the subscriber Tn1, the final selector is again set on the contact 1. After the testing to see whether this is free the contacts 14h, 15h and 16h are closed, by the control switch of the final selector. Thus over the c-conductor a circuit is first made for the relay F1 which in this case extends from earth, battery, relay T1 in the preselector, relay F1 (winding I) contacts 4g1, 5f1, c-arm of the final selector on contact 1, contact 16h directly to earth. Relay F1, therefore, operates again and, in the manner already described, by opening the contact 5f1 connects the winding II of the relay G1, which now over the contact 6g1, short-circuits the winding I of the relay F1 while at the same time, over the contact 7g1, windings II of the relays F and G are connected. These two windings are now in parallel to the the contact 16h in the c-conductor of the final selector 50 seized, which extends directly to earth potential. The two windings are therefore short-circuited so that the relay F1 whose winding is already short-circuited over the contact 6g1, restores and remains disconnected for the duration of the connection; the relay G1 remains energized in the test conductor, however. The contacts 8f1 and 9f1 are restored to normal so that the calling current sent out from the final selector extends over the following path: alternating current 55 source contact 15h, b-arm of the line selector to contact 1, contact 8f1, a-conductor of the junction line, contact 10u2, relay U1, subscriber's set Tn1, condenser K1, contact 11u1, earth. Therefore, in spite of the connection of calling current 60 65 70 75 80 85 90 95 100 105 110 115 120 125 130 135 140 145 150 155 160 165 170 175 180 185 190 195 200 205 210 215 220 225 230 235 240 245 to the other lead the calling subscriber $Tn1$ is reached over the a -conductor. When he replies there follows the connection to the common line in the manner already described. On the release 5 of the connection after the release of the final selector, the winding II of the relay $G1$, which has been short-circuited over contact $16h$ in the final selector, energizes and effects the release 10 of this relay as it works in opposition to winding I .

In the case of an incoming high valued connection to the subscriber $Tn2$, corresponding switching operations take place which are only differentiated in that the final selector is set on the 15 contact 2 so that the alternating calling current connected over the contact $15h$ extends over the b -arm of the final selector to contact 2 , contact $8f1$ in the normal position, b -lead of the junction line, contact $12u1$, relay $U2$, subscriber's set $Tn2$, 20 condenser $K2$, contact $13u2$ to earth.

The arrangements for making outgoing connections are not described in detail since they are not of interest in connection with the present 25 invention.

Fig. 2 relates to a system in which the calling current is connected at the final selector (OFLW2) in the same way (over the control switch contacts $17h$ or $18n$) to the a -conductor of the final selector for incoming high and low valued 30 connections. Since, however, a differentiation between incoming high and low valued connections is undertaken by the control switch of the final selector it is possible by using the switching device already described in Fig. 1 to characterize 35 the incoming local and trunk connections at the connected subscriber's set.

In the case of incoming low valued connections, after the setting of the final selector on the contact of the calling set the following circuit is 40 closed: earth, battery, relay $T2$ in the preselector, c -conductor, relay $F2$ (winding I), contact $19g2$, $20f2$, c -arm of the line selector on contact 3 , control switch contact $21n$, relay $P2$, earth. The switching relay $F2$ operates and in the manner 45 already described with reference to Fig. 1, operates the auxiliary relay $G2$ which connects its winding II and thus, also the winding II of relay $F2$. Since the low valued connection is concerned, the relay $F2$ remains energized with its winding II parallel to the relay $P2$ in the final selector and operates its contacts $22f2$ and $23f2$. The calling current of the final selector therefore 50 extends over the contact $18n$, a -arm of the final selector, contact 3 , contact $22f2$, a -conductor of the junction line, switchhook $24hu$, bell Wn , earth. The bell for low valued connections sounds and gives the calling subscriber an indication of the kind of incoming connection. When 55 the calling subscriber replies, the bell as disconnected together with the bell for high valued connections connected over the b -conductor.

In the case of incoming high valued connections, the energizing of relay $F2$ takes place due 60 to the earth potential connected directly over the control switch contact $25h$ in the final selector. In this way, after the operation of relay $G2$ in the manner already described, the winding II of the relay $F2$ is short-circuited also in the manner 65 described so that the relay $F2$ immediately restores and the contacts $22f2$ and $23f2$, respectively remain in their rest position for the duration of the connection. The calling current sent 70 out from the final selector therefore extends from the calling current source over: contact $17h$, a -arm of the final selector on contact 3 , contact 75

$22f2$, b -conductor of the junction line, switch hook contact $26hu$, bell Wn to earth. The alarm bell Wn for high valued connections sounds and does this in a different tone to the sound produced for low valued connections. When the 5 subscriber lifts his receiver the calling circuit is interrupted and the conversation can be proceeded with.

The release of the switching over device takes place in the manner described in connection with 10 Fig. 1.

What is claimed is:

1. In an automatic telephone system arranged for local and toll calls, a line, switching means individual to said lines, a connector switch operated to connect with said line when either a local or a toll call is extended thereto, and a source of signalling current in said switch, said switching means controlled according to the value of the connection extended to said line to determine the 20 conductor of the line over which said signalling current shall be transmitted.

2. In a system as claimed in claim 1 in which the switching means reverses the conductors of 25 said line upon operation.

3. In an automatic telephone system arranged for local and toll calls, a line, a connector switch operated to connect with said line when either a local or a toll call is extended thereto, a test circuit for said switch, switching means individual to said line controlled over said test circuit to determine the conductor of the line over which signalling current is to be transmitted, means effective when a local call is extended to said line for connecting ground to 30 said test circuit through a test relay of said connector to thereby control said switching means, and means effective when a toll call is extended to said line for connecting direct ground to said test circuit to thereby control 35 said switching means.

4. In a system as claimed in claim 3, wherein said switching means is operated over said test circuit when either a local or a toll call is extended, and means controlled responsive 45 to the extension of a toll call for immediately restoring said switching means to normal.

5. In a system as claimed in claim 3, wherein said switching means comprises a two winding relay, the first of said windings connected in 50 series with said test circuit and the second of said windings connected in parallel with the test relay in the test circuit of said connector and functions as a holding winding.

6. In a system as claimed in claim 1, an auxiliary relay associated with said switching means operated responsive to the extension of a toll call to said line to thereby render said switching means ineffective.

7. In an automatic telephone system arranged 60 for local and toll calls, a line, switching means individual to said line, a connector switch operable to connect with said line responsive either to a local or toll call, a source of signalling current, means responsive to the operation of 65 said switch to connect with said line for connecting said signalling current thereto, a switching means controlled according to the value of the connection for determining over which conductor of the line the ringing current is to be 70 transmitted, an auxiliary differential wound relay associated with said switching means operated over a circuit including one of its windings responsive to the extension of a toll call to render said switching means ineffective, and 75

means effective upon the release of an established connection for completing an energizing circuit for both windings of said relay to restore the same to normal.

- 5 8. In a telephone system, a line, a connector switch for extending local or toll calls to said line, a test circuit for said switch, a source of ringing current in said switch, switching means individual to said line and included in
- 10 said test circuit for determining the conductor of the line over which the ringing current is to be transmitted when a connection is extended thereto, and means in said connector for connecting ground through a resistance to said
- 15 test circuit when a local call is extended and for connecting direct ground to said test circuit when a toll call is extended and thereby control the operation of said switching means.
9. In a telephone system, a line, a station on
- 20 said line, a pair of signalling devices for said station, an exchange switch, said switch adapted to be operated for the extension of either a toll or local connection to said line, a source of sig-

nalling current in said switch, and means for connecting said signalling current to said line, said signalling current connected to one conductor of said line to actuate one of said signals when local calls are extended and connected to the other conductor of said line to actuate the other of said signals when toll calls are extended.

- 10 10. In a telephone system, a line, a station on said line, two separate signals at said station, a circuit for each signal, a switch adapted to be directly operated to extend either a local or a toll call to said station, a source of signalling current in said switch, means responsive to the extension of a local call to said station for connecting said signalling current to said line over one circuit to actuate only one of said signals, and means responsive to the extension of a toll call to said station for connecting said signalling current over the other circuit to said line to actuate only the other of said signals.
